UNITED STATES PATENT OFFICE

GEORGE S. KEHL, OF CHICAGO, ILLINOIS

ADVERTISING SHEET FORM

Application filed March 15, 1930. Serial No. 436,153.

This invention relates to correspondence and advertising forms and is particularly adapted to be used with advertising forms in connection with which a return envelope 5 is desired.

One of the objects of the invention is to provide forms which may suitably be used in folders, books or any ordinary correspondence envelopes, which forms are provided 10 with means by which a portion thereof may be removed to provide a return envelope. Another object is to provide a sheet which may serve to convey information or an advertisement to the addressee, a portion of which 15 may be removed to provide a return envelope and a space within the envelope upon which a message may be written. A still further object is to provide sheets of regular or normal size which are provided with weakened 20 or perforated lines along which a section may be removed to form a return envelope, certain edges of the removed segment being provided with adhesive would serve to bind together the sides of the envelope. Other objects and 25 advantages will appear as the specification proceeds.

The invention is fully described in the following specification and shown in the accompanying drawings in which,

30 Figure 1 is a perspective view of a folder or booklet containing a sheet embodying my invention; Fig. 2 is a rear view of the sheet shown in Fig. 1; Fig. 3 is a front view of a separate sheet embodying my invention; and 35 Fig. 4 is a view of the rear side of the form of sheet shown in Fig. 3.

In the illustration given, 1 designates a sheet which may be separate or secured, as shown in Fig. 1, in a folder, magazine or the like. Sheet 1 is preferably of uniform or regular size and shape, having four straight sides. Written matter may be placed upon the sheet as upon any other sheet which is used in correspondence or for advertising. 40 Preferably, for reasons hereinafter given, the matter appearing upon the sheet is printed thereon.

To provide a return envelope, a transverse or oblique line 2 is indicated on the sheet 45 along which the sheet may be separated into

an upper part 3 and a lower part 4. The lower part 4 has two side portions 5, a bottom corner portion 6 and an envelope flap portion 7. The sides 5 may be turned inwardly over a body portion 8 and the bottom end portion 55 6 may be turned upwardly to engage and hold the sides 5 in position. To facilitate the folding of the envelope, lines 9 may be drawn upon the sheet.

Adhesive 10 may be applied to the edges of 60 the lower portion 6 and to the edges of the flap portion 7 and dried. When the gum or adhesive 10 on the lower corner portion 6 is moistened and the piece is applied to the sides, it will serve to hold the sides in position and thus form the envelope receptacle. 65 If desired, instead of applying adhesive to the edges of the corner piece 6, adhesive may be applied to the sides 5. When the adhesive on flap 7 is moistened and folded over, it will 70 serve to seal the envelope for mailing.

The space 8 within the envelope may be provided with lines or space for a return message and certain form statements, may, if desired be printed thereon.

75 On the opposite side of sheet 1, and on segment 4, the exterior of the envelope, or the address side of the envelope is provided. This side may be printed with suitable legends, indicating that it is the reply envelope, and 80 with lines for the address, etc.

In preparing the form, it is preferred to first print the letter or advertisement upon the front face of the sheet. This printed matter may be kept wholly on the segment 3, as 85 shown in Fig. 1, or, as shown in Fig. 3, it may cover the major portion of the page. After the printing has been completed, the edges 10 are provided with gum or other adhesive which is allowed to dry. The various 90 lines required to aid in the folding operation may be printed either before or after or simultaneously with the printing of the information upon the front sheet. The line 2 may be weakened, in any desirable manner, to enable 95 the parts 3 and 4 to be readily separated. As shown in Figs. 3 and 4, the line 2 is perforated. While the line 2 has been indicated in the illustration as of a certain form, it is understood that the line may be modified in 100

direction and shape so as to provide envelopes of different shapes. For example, the line forming the flap 7 may be modified so as to form a rectangular shaped flap instead of a 5 somewhat inverted V-shaped flap.

By forming the division line at a somewhat slanting or oblique angle, it is obvious that the sides and bottom flap of the envelope are formed without further change or modification. The gum which is placed along the 10 lower flap 10 is on the very edge of the envelope and therefore does not come in contact with any of the written matter. The gum 10 on flap 7 is placed thereon preferably after the printing has been completed and, when in 15 dried form, interferes very little with the printed matter on the page. In the illustration given in Fig. 1, the flap 7 is below the printed matter.

20 By employing a sheet of regular stock size or of uniform dimensions for this purpose, the expense of providing advertisement, return envelope and return message is considerably reduced; while, at the same time, the sheet is adapted for use in magazines, trade-folders and the like.

The foregoing detailed description has been given for clearness of understanding only and no unnecessary limitations should 30 be understood therefrom, but the appended claims should be construed as broadly as permissible in view of the prior art.

I claim:

1. In forms of the character described, a 35 sheet having regular straight sides, said sheets being provided with a transverse line along which said sheet may be separated, one of said separated portions being adapted to be folded to form a return envelope.

40 2. In forms of the character described, a sheet with four regular straight sides and provided with a slanting line along which said sheet may be separated, one of said separated portions being adapted to be folded 45 to form a return envelope.

3. In forms of the character described, a quadrilateral sheet having straight sides provided with an oblique line of division, one of the divided segments being adapted to 50 be folded to form a return envelope, and means for securing together the folded sides of said envelope.

4. In forms of the character set forth, a sheet in the shape of a parallelogram and 55 having a slanting line of division, said sheet along said line being weakened to enable ready separation of the parts, one of the separated parts being adapted to be folded to form a return envelope, and means for securing together the sides of said envelope.

5. In forms of the character described, a sheet in the shape of a parallelogram and 60 having a weakened line of division along which said sheet may be separated, one of 65 said separated portions being adapted to be

folded to form a return envelope, and adhesive disposed upon certain edges of said separated portion and adapted to seal the sides of said envelope.

6. In forms of the character described, a 70 sheet with four regular straight sides and having a slanting perforated line of division, one of the parts adapted to be separated being foldable to form a return envelope, and means for sealing the sides of said envelope. 75

7. In forms of the character described, a four-sided sheet having regular and straight sides and provided with a diagonal line of division, one of the parts adapted to be separated being foldable to form a return envelope and means for securing together the 80 sides of said envelope.

8. In forms of the character described, a sheet in the shape of a parallelogram and 85 provided with a transverse line of division, one of said segments formed by the division being substantially triangular and the corner portions of said triangular segments being foldable inwardly to form an envelope, and means for securing the sides of said envelope. 90

9. In forms of the character set forth, a folder provided with a sheet having straight regular sides and having a slanting line of division, one of the divided portions being adapted to be folded to provide a return 95 envelope, and means for sealing the sides of said envelope.

10. A four sided sheet adapted for use in a magazine and the like, having four straight and regular sides and having also a weakened 100 line of division, said sheet having adhesive applied to certain portions thereof along which said sheet may be separated, one of said divided portions being adapted to be folded to form a return envelope, and said 105 adhesive serving to seal the sides of said envelope.

11. In forms of the character described, a sheet in the shape of a parallelogram provided with a substantially diagonal line of 110 division, one of the segments formed by the division being substantially triangular and the corner portions of said triangular segment being folded inwardly to form an envelope, and means for securing the sides of 115 said envelope.

GEORGE S. KEHL.
